STENCIL PRINTING MACHINE

Harmon P. Elliott, Watertown, Mass.

Application February 26, 1949, Serial No. 78,509

5 Claims. (Cl. 101—48)

1

This invention relates to improvements in stencil printing machines and more particularly to portable manually operated printing machines of the general type wherein a printing device, such as a stencil, for example, is moved from a supply of printing devices to a printing position at which a printing roll is manually operated to print from the printing device on a work sheet or card at the printing position.

In my Patent No. 2,338,170, granted January 4, 1944, there is disclosed a printing machine of the general type to which the present invention relates but, in the patented machine, the operator is required to manually actuate the stencil feed mechanism prior to each manual printing operation.

It is among the objects of the present invention to provide a printing machine of the mentioned general type wherein a new printing device is moved to printing position automatically in response to each manual printing operation.

Another object is to provide a printing machine of the mentioned general type wherein one printing device holder holds a supply of printing devices in a stack at one side of the printing position and another printing device holder is located at the opposite side of the printing position for receiving printing devices which have passed through the printing position, and wherein a manual printing actuation of the printing mechanism sets a printing device advancing mechanism for automatic advance of the lowermost printing device in the supply stack to printing position during the return movement of the printing mechanism, with simultaneous advance of a printing device beyond the printing position into the receiving holder.

Still another object is to provide a printing machine of the mentioned general type wherein stencils are held in a supply stack and a stencil advancing slide is biased in stencil advancing direction and is pulled in opposition to its bias to a position to engage the lowermost stencil in the supply stack, in response to a printing operation of the machine.

It is, moreover, my purpose and object generally to improve the structure and operation of printing machines, and especially printing machines of the portable manually operated type which print from stencils or comparable printing devices.

In the accompanying drawings:

Fig. 1 is a top plan view of a manually operable stencil printing apparatus embodying features of the invention;

2

Fig. 2 is an end elevation of the apparatus of Fig. 1, with portions broken away, the operating lever being shown by dotted lines in its stencil printing position;

5 Fig. 3 is a perspective view of the stencil tracks or rails, and the pivoted carrier plate therefor, the slide for advancing the stencils being shown by dotted lines;

10 Fig. 4 is a perspective view of the stencil advancing slide and its spring-return mechanism; and

15 Fig. 5 is a perspective view of a stencil of the general type from which the illustrated printing apparatus accomplishes its printing.

15 Referring to the drawings, a base or platen 10 supports all of the operating parts of the machine, and the under side of the base preferably is equipped with protective feet 12, of rubber, or the like, to avoid marring of a desk or 20 table on which the machine may rest.

The usual printing roll 14 is carried at the forward ends of the two arms 16 of a rocker frame indicated generally at 18, and an ink roll 20 constantly engages the printing roll, being carried 25 at the forward ends of levers 22 whose rear ends are pivoted at 24, respectively, on the opposite arms 16 of the rocker frame 18. Springs 26, extending between the respective levers 22 and arms 16, hold the ink roll in contact with 30 the printing roll.

The rocker frame 18 is pivotally mounted on the opposite end portions of a shaft 28 whose ends extend through rearwardly extending portions of arms 16 into the fixed side bracket supports 30 which are secured at 32 to base 10 and extend upwardly and forwardly, with their forward portions rigidly connected together by the plate part 34. Two coiled springs 36 have their upper ends connected to plate part 34 and their 35 lower ends connected to a cross bar 38 of the rocker frame, whereby the springs constantly bias the forward portion of the frame upwardly, tending to hold the printing roll 14 in an elevated position.

40 45 A stencil track extends under the elevated printing roll 14, the track comprising the spaced rails 40 whose opposed edges are grooved at 42 for receiving the opposite side edge margins of stencils 44 which are movable along the track 50 from a stencil holder 46 wherein a supply stack of the stencils 44 is held above one end of the track. The stencils move along the rails to and through a printing position underneath printing roll 14, being pushed in succession along the rails 55 to the stencil holder 48 at the other end of the

track. At the locations of the stencil holders 46, 48, the upper walls of the edge grooves of the track rails 40 are cut away, as at 50, 52, respectively, whereby the lowermost stencil of the stack in holder 46 rests directly on the lower walls of the track grooves, in position to be moved out of the stack along rails 40 by means later to be described. At the location of holder 48, the lower walls of the track grooves have protuberances (not shown) thereon and the stack of stencils is supported on the protuberances with the lowermost stencil a little above the plane of the top surface of the under walls of the track grooves, whereby a stencil moving along the track engages under the lowermost stencil in the stack and is pushed into the stack with a slight elevating of the entire stack of stencils, so that each newly entered stencil becomes the lowermost one in the stack, as is well known in the art.

Track rails 40 are mounted on a plate member indicated generally at 54 and best seen in Fig. 3. The rails are secured to plate member 54, as by the screws 56, there being an opening 58 in the plate, between the rails, through which the printing roll 14 engages a stencil when a printing is to be effected from a stencil. Member 54 has rearwardly extending arms 60 thereon terminating in the cylindrical part 62 through which shaft 28 extends, or the part 62 may be solid with end trunnions for pivotally mounting plate member 34 and rocker frame 18, at 28. In any case, however, the plate member 34 and the rocker frame 18 will be separately pivoted at 28, so that each is free to swing about its pivot independently of the other. However, a pair of leaf springs 64 engage under the rear rail 40, as best seen in Fig. 2, and these springs constantly urge the plate member 54 in counter-clockwise direction about pivot 28, as viewed in Fig. 2, so that plate member 54, and the elements carried thereon, follow the printing roll 14 upwardly when the rocker frame 18 swings counter-clockwise about its pivot 28 in Fig. 2, and the plate member 54 is forced downward, against the bias of springs 64, during each clockwise swinging of rocker frame 18, as viewed in Fig. 2.

The forward ends of leaf springs 64 are bent downward generally at right angles, as at 65, and openings 66 through base or platen 10 accommodate these forward ends of the spring when the plate member 54 is depressed. Also, these portions 65 of the springs constitute stops for engaging the inner edge of a work sheet W to properly position the work sheet at the printing position. The springs 64 preferably will be interconnected and adjustable as a unit for varying the location of the inner edge of a work sheet W.

It is desirable to provide lost motion between the printing roll 14 and the track carrying plate member 54 when the printing roll moves toward printing position. As herein shown, the printing roll shaft 15 has its ends extending loosely through upstanding ears 66 on plate member 54, the ears being slotted at 67 so that the roll 14 can move downwardly a substantial distance before forcing the plate member 54 downward.

A customary ratchet mechanism (not shown) operates to rotate the printing roll a little in response to each printing operation of the apparatus, thereby to present different portions of the surface of the roll for printing coaction with successive stencils.

The printing roll 14 is actuated to printing position by the actuating lever 68 which is equipped with a hand grip 70. The lever is pivotally con-

nected at 72 to the extreme rear ends of the arms 16 of rocker frame 18, the lever having the feet portions 74 depending below the pivot 72, and each foot having a roller 76 thereon engaging the base 10 between two stop lugs 78, 80 at opposite sides of the base 10, at the rear thereof. When the lever 68 is manually actuated from its full line position to its dotted line position, in Fig. 2, the rollers 76 roll rearward along base 10 from engagement with stops 78 into engagement with stops 80, and the printing roll moves down, ultimately forcing the plate member 54, and the elements carried thereon, downward to effect a printing.

When lever 68 is actuated to its dotted position in Fig. 2, a stencil will be in printing position for coaction with printing roll 14 and platen 10. When the lever is released and is returning to its full line position of Fig. 2, the lowermost stencil in the supply stack at 46 will be advanced along the track rails 40 to printing position, pushing the stencil which previously was in printing position toward the stencil holder 48.

According to the invention, a stencil advancing slide 82 is actuated in response to movements of lever 68. The slide 82 is mounted on the forward one of the rails 40, and has an upstanding ear 84 to which one end of a flexible wire 86 is secured, as at 88. Wire 86 extends from ear 84 to the left hand end of the apparatus, as seen in Fig. 1, where it passes through a fixed guiding bracket 90, to which a flexible casing 92 is secured, the casing extending rearward to a fixed bracket 94 and having its rear end fixed to the upper end of bracket 94, as at 96. Wire 86 has guided extent through casing 92, it extending out of the casing through bracket 94, with its rear end connected to one end of a coil spring 98 whose other end is connected at 100 to the hand grip portion of actuating lever 68. Hence, when lever 68 is actuated to its dotted position in Fig. 2, slide 82 is drawn by wire 86 toward the left hand end of the apparatus as viewed in Fig. 1.

As best seen in Fig. 4, a stiff rod 102 has one end fixed at 104 to ear 84 of slide 82. The rod extends from ear 84 to the right, in Fig. 1, it passing loosely through a fixed bracket 106 and having substantial extent beyond bracket 106 when the slide is in its position of Fig. 1. An enlargement 108 on the end of rod 102 is adapted to engage bracket 106 to limit the travel of the slide 82 to the left. A long coil spring 110 has one end connected to ear 84 of the slide and has its other end connected to fixed bracket 106, whereby the slide constantly is biased to the right along its supporting rail 40, as viewed in Fig. 1. A stop element 112 may be provided on rod 102 for engaging bracket 106 to limit travel of the slide to the right, in Fig. 1.

Slide 82, at the inner edge of its supporting rail 40, and at the left-hand end of the slide, has a portion 114 providing a shoulder 116 which is adapted to engage back of the edge of the lowermost stencil in the supply stack when the slide is drawn to the left by a manual actuation of lever 68. As the slide moves to the left, the leading part of portion 114 rides under the lowermost stencil, with a slight lifting of the stack. As soon as shoulder 116 passes beyond the lowermost stencil, the stack settles back and shoulder 116 will be in position to engage the adjacent edge of the lowermost stencil when the slide moves to the right, as viewed in Fig. 1. Such movement of the slide to the right is effected by the coil spring 110 as soon as actuating lever 68 is released and

moves rearward to its full line position of Fig. 2, the stop element 112, or the like, stopping the slide with the picked-up stencil in printing position, ready for coaction with printing roll 14 on the next printing actuation of lever 68.

It will be obvious from the foregoing description, in connection with the drawings, that the operator needs to give no thought to the stencils as manual printing of work sheets or cards proceeds, the stencils being automatically removed from the supply stack of stencils and advanced in succession to printing position in response to manual printing actuations of the lever 68. Also, each stencil advanced to printing position pushes the preceding stencil along rails 40 toward the stencil holder 48 into which the stencils deliver in succession at the bottom of the stack of stencils therein.

It is intended that the patent shall cover, by suitable expression in the appended claims, whatever features of patentable novelty exist in the invention disclosed.

I claim as my invention:

1. In a printing apparatus, a platen, a pair of rails mounted above the platen and constituting a track along which printing devices may be moved in succession to and through a printing position, means for holding a stack of printing devices to one side of the printing position with the lowermost printing device of the stack resting on said rails, a printing roll above the platen at said printing position, means for moving the printing roll toward and away from said platen, a slide member movable along said rails and having an abutment thereon for engaging back of an edge of the lowermost printing device in said stack of printing devices when moved in one direction along said rails, a flexible element connected to said slide member and to said means for moving the printing roll whereby a movement of the printing roll toward said platen effects a movement of said slide member in direction to engage its said abutment back of an edge of the lowermost printing device in said stack, and resilient means constantly biasing said slide member in the opposite direction along said rails for moving said slide member and an engaged lowermost stencil in the said stack toward said printing position simultaneously with any movement of said printing roll away from said platen.

2. In a printing apparatus, a platen, a pivotally mounted printing roll arranged for printing coaction with the platen at a printing position, means for holding a stack of printing devices to one side of the printing position, manual means for actuating the printing roll into printing coaction with the platen, means biasing the printing roll in direction away from the platen whereby the printing roll moves out of printing relation to the platen when said manual means is released, a slide member movable between first and second positions and having an abutment means thereon for engaging back of an edge of the lowermost printing device in said stack of printing devices when said slide member is moved to said first position, a flexible element connected to said slide member and to said manual means whereby a manual movement of said manual means, to actuate the printing roll into printing coaction with the platen, effects a movement of said slide member to its said first position in which its said abutment engages back of an edge of the lowermost printing device in said stack, and resilient means constantly biasing said slide member to its said second position for moving the slide member and

an engaged lowermost stencil in said stack toward said printing position in response to a said movement of the printing roll away from said platen when said manual means is released, the said movement of the slide member to said second position effecting a movement of the engaged printing device to said printing position.

3. In a printing apparatus, a platen, a pivotally mounted printing roll arranged for printing coaction with the platen at a printing position, means for holding a stack of printing devices to one side of the printing position, track rails along which printing devices move in succession from said stack to said printing position, each lowermost printing device in the stack resting on said rails, a lever manually operable for moving the printing roll toward the platen, means for moving the printing roll away from the platen following each manual operation of said lever, a slide member for engaging back of the lowermost printing device in the stack and then movable to advance the engaged printing device along the rails to said printing position, a spring resiliently biasing the slide member toward said printing position, a flexible tensile element connected to said slide member and to said lever whereby said slide member is moved in direction to tension said spring and to engage the slide member back of the lowermost printing device in the stack when said lever is operated to move the printing roll toward said platen, the energy stored in the tensioned spring moving the slide member to advance the engaged printing device to printing position when said lever is operated to move the printing roll away from said platen.

4. In a printing apparatus, a platen, a printing roll pivotally mounted for printing coaction with the platen, manually operable means for moving the printing roll about its pivot in general direction toward the platen, means for moving the printing roll in general direction away from the platen following each manual movement thereof toward the platen, a supply receptacle for holding a stack of printing devices at one side of the printing roll, a receiving receptacle at the opposite side of the printing roll for holding a stack of printing devices delivered thereto, track rails extending between the two said receptacles and passing between said printing roll and platen, a slide member movable in opposite directions along said rails between first and second positions in the first of which the slide member engages back of an edge of the lowermost printing device in said supply receptacle preparatory to pushing the engaged printing device to printing position between the printing roll and the platen as the slide member moves from said first position to said second position, a flexible element tying together said slide member and said manually operable means whereby a manual operation of the manually operable means effects a movement of said slide member to said first position, and resilient means constantly biasing said slide member toward said second position whereby said resilient means moves said slide member from said first position to said second position when said manually operable means is released for return movement following a said manual operation thereof, said slide member, when moving to said second position, pushing the engaged printing device ahead of it along said rails to said printing position between the printing roll and the platen.

5. In a printing apparatus having a platen and a printing roll arranged for printing coaction at a printing position and having printing devices

movable in succession into a printing position between the platen and printing roll, a slidably mounted member for engaging and moving successive printing devices to the printing position, a manually operable lever for manually effecting a printing coaction between the platen, the printing roll and a printing device at said printing position, a flexible tensile element tying together said slidably mounted member and said manually operable lever whereby a manual operation of said manually operable lever effects a movement of said slidably mounted member to a first position in which it engages a said printing device which is to be moved to said printing position, and a spring constantly biasing said slidably mounted member to a second position and operative to move said slidably mounted member from said first position to said second position when said manually operable lever is released for return movement following a said manual operation 20

thereof, said slidably mounted member, when moving from said first position to said second position, being adapted to push the engaged printing device ahead of it into said printing position.
